DESIGN FOR A LINKED CHAIN

Harry Sheer, New York, N. Y., assignor to City Novelty Corporation, New York, N. Y.

Application July 28, 1939, Serial No. 86,286

Term of patent 3½ years

To all whom it may concern:

Be it known that I, Harry Sheer, a citizen of the United States and a resident of New York city, county of Kings, and State of New York, have invented a new, original, and ornamental Design for a Linked Chain, of which the following is a specification, reference being had to the accompanying drawing, forming part thereof.

I claim:
The ornamental design for a linked chain, substantially as shown.

HARRY SHEER.
